(57) **CLAIM**

The ornamental design of a housing for a data synchronization cable, as shown and described.

DESCRIPTION

FIG. 1 is a front perspective view of a housing for a data synchronization cable in an extended condition, showing our new design;

FIG. 2 is a front perspective view thereof, in a retracted condition;

FIG. 3 is a front elevation view thereof;

FIG. 4 is a rear elevation view thereof;

FIG. 5 is a right side elevation view thereof;

FIG. 6 is a left side elevation view thereof.

FIG. 7 is a top plan view thereof; and,

FIG. 8 is a bottom plan view thereof.

In the drawing views, the broken line represents unclaimed environment only and forms no part of the claimed design.

1 Claim, 6 Drawing Sheets

FIG. 3

FIG. 4

FIG. 7

FIG. 8
